UNITED STATES PATENT OFFICE.

MORTIMER S. PARKHILL, OF LITTLETON, COLORADO, ASSIGNOR TO INGERSOLL-RAND COMPANY, OF JERSEY CITY, NEW JERSEY, A CORPORATION OF NEW JERSEY.

MOUNTING.

Application filed January 26, 1922. Serial No. 533,051.

To all whom it may concern:

Be it known that I, MORTIMER S. PARKHILL, a citizen of the United States, and a resident of Littleton, county of Arapahoe, State of Colorado, have invented a certain Mounting, of which the following is a specification accompanied by drawings.

This invention relates to mountings and particularly to a mounting for hoists or other machines which is adapted to be bolted down to a flat surface, such as the platform of a mine car, stone boat or other vehicle or any timber structure or support, so that it shall have the capacity of oscillation about its perpendicular axis.

Small air driven hoists, for instance, of which the so called "little tugger" is a well known example are used for many lifting, hauling and handling jobs. Miners use them in a variety of ways, clamped to various forms of supports for lowering, raising, hauling, dragging, and numerous other purposes. They are also used, among other places, on board ship, in structural steel work, in manufacturing and power plants, and in fact in every place where a small compact powerful unit is desired.

In using such hoists or in fact in using almost any machine adapted to be mounted by means of clamps, occasions arise in which it becomes necessary or desirable to change the operative position or adjustment of the device in the working plane.

The objects of the present invention are to enable a hoist or other device to be quickly changed and adjusted at will to any position in the working plane by the simple expedient of rotation, the mounting being of few parts and readily assembled and disassembled; rugged in character; and specifically in the case of the application of a hoist as above mentioned, to enable the mounting to be bolted down to the floor of a mine car, stone boat or other base and quickly and easily rotated in order that the rope may be led off straight from the drum in any direction in the working plane.

To these and other ends, which will hereinafter appear, the invention is shown in one of its preferred forms in the accompanying drawings, in which

Figure 1 is a side elevation partly in lon-

gitudinal vertical section, showing a "little tugger" hoist for illustrative purposes mounted longitudinally on a timber platform or base by means of my mounting; taken on the line 1-1 of Figure 2;

Figure 2 is a top plan view of the mounting partly in section, taken on the line 2-2 of Figure 1;

Figure 3 is a detail transverse sectional view through one end of the mounting, taken on the line 3-3 of Figure 2;

Figure 4 is a perspective view of the cone member or swivel forming a part of the mounting.

Referring to the drawings, a base or support A is shown, partly broken away, to which the base plate B of the mounting is adapted to be secured by means of bolts 70 (not shown) adapted to pass through the holes C located at the four corners of the plate B. A stationary abutment member D is formed on the base plate B approximately centrally thereof, this abutment D being undercut, forming an open semi-circular flared recess E, and being preferably reinforced by means of a plurality of ribs F, formed integrally therewith and joining the end of base plate B.

A movable clamping member G is slidably mounted on the base plate B at its opposite end, this movable clamping member G having a portion H projecting centrally thereof. The portion H is undercut at the 85 end to form a semi-circular flared recess J corresponding to and concentric with the recess E of the abutment D.

The movable clamping member G is mounted to slide freely longitudinally in 90 the base plate B toward and away from the abutment member D, having for this purpose, a longitudinal flanged web K which is adapted to slide in a corresponding groove L in the raised central portion O of the base 95 plate B. Sliding movement of the clamping member G is effected by a plurality of side rods or bolts P having heads Q, these heads fitting in undercut sockets R at the end of the clamping member G, the body 100 portions of the bolts passing through longitudinal recesses S in the under side of the clamping member G, through holes T at the outer sides of the abutment member D

and thence through ears U uprising from the base plate B at its opposite end, where screw threaded means in the form of a plurality of nuts V are employed to move the 5 rods longitudinally and secure the clamping member G in position against the article to be clamped.

For a portion of their length adjacent to the clamping member G the bolts traverse 10 longitudinal supporting and guiding ribs W formed on the base plate B in alignment with the recesses S.

A swivel X, forms a part of the mounting, but also, necessarily, becomes a part of 15 the hoist or other machine to be mounted. This swivel X includes a circular cone base Y and a plate Z. The hoist or other machine a is bolted to the plate Z by bolts b passing through holes d in the plate Z and 20 the cone base Y fits within the undercut semi-circular recesses E and J of the members D and G respectively, and rests upon the base plate B. The base plate B is cut 25 away at this point, indicated at e, to reduce the friction and facilitate rotation of the machine mounted on the swivel X. The longitudinal recesses S and holes T through which the side rods P pass, are in substantially the same plane as the undercut recesses E and J, so that a powerful clamping 30 grip on the cone base Y of the swivel is obtained.

By means of this form of mounting rotation of the machine in the working plane is 35 permitted in any direction and to any degree. When the desired position has been determined the nuts V are tightened, sliding the clamping member G toward the abutment D, clamping the cone disk Y securely 40 between them.

The device is disassembled with facility, removal of the cotter pins f and nuts V permitting the member G to slide out of the base plate B, whereupon the rods F readily 45 drop out of the undercut recesses S, the base plate B remaining secured to the support A.

It will be noted that the hoist a extends laterally beyond the swivel Z and its cone base Y. The hoist a extends also laterally 50 over the greater part of the base plate B.

For the sake of accessibility, the ears U are located a convenient distance beyond the lateral limit of the hoist a and the bolts P are made correspondingly long to extend 55 through the ears U, so that, the nuts V may be turned without the use of a special wrench. This arrangement adds to the facility with which the hoist a may be adjusted on the base B.

60 I claim:

1. A mounting of the character set forth, comprising a flat base plate adapted to be secured to a suitable support, a stationary abutment member formed on said 65 base plate having a semi-circular opening

adapted to receive an article to be clamped, a longitudinally freely movable clamping member slidably mounted on said base plate adjacent to one end, said movable clamping member having a projection with a semi-circular opening corresponding with the opening of the stationary abutment member, a central longitudinal flanged web beneath said movable clamping member, said web being adapted to slide in a corresponding central groove in said base plate, side rods on opposite sides of said groove, longitudinal ribs formed on the base plate, said side rods being supported and guided on said ribs, and said movable clamping member being supported and guided on said side rods and in said central groove of said base plate, and means on said side rods adjacent to said stationary abutment for moving said clamping member toward said stationary abutment member to effect clamping action of the stationary and movable members about the article to be clamped. 70 75 80 85 90

2. A mounting of the character set forth, comprising a flat base plate adapted to be secured to a suitable support, a stationary abutment member formed on said base plate having a semi-circular opening adapted to receive an article to be clamped, a longitudinally freely movable clamping member slidably mounted on said base plate adjacent to one end, said movable clamping member having a projection with a semi-circular opening corresponding with the opening of the stationary abutment member, a central longitudinal flanged web beneath said movable clamping member, said web being adapted to slide in a corresponding central groove in said base plate, side rods on opposite sides of said groove secured in said movable clamping member and passing through longitudinal recesses in the under side of said movable clamping member, and through the stationary abutment member, longitudinal ribs formed on the base plate in alignment with the longitudinal recesses, said side rods being supported and guided on said ribs and said movable clamping member being supported and guided on said side rods and in said central groove of said base plate, and means on said side rods adjacent to said stationary abutment for moving said clamping member toward said stationary abutment member to effect clamping action of the stationary and movable members about the article to be clamped. 95 100 105 110 115 120 125

3. A swivel mounting for a hoist comprising, a swivel, a base plate extending beyond the lateral limits of the hoist in any position thereof, stationary and longitudinally freely movable concentrically undercut clamping members adapted to embrace opposite sides of said swivel, said movable clamping member having a web and being slidably in a groove in said base, separate longitudinal 130

rods on opposite sides of said web engaging the movable clamping member at one end and passing through recesses in said movable and stationary clamping members and through the opposite end of the base plate, and means on the rods at said opposite ends beyond the lateral limits of said hoist for

moving said movable clamping member toward and away from the stationary member to secure said members and swivel in clamped relationship. 10

In testimony whereof I have signed this specification.

MORTIMER S. PARKHILL.
